STAPLING MACHINE

Samuel Segal, New York, N. Y., assignor to Wilson Jones Company, New York, N. Y., a corporation of Massachusetts

Application February 23, 1951, Serial No. 212,229

10 Claims. (Cl. 1—3)

This invention relates to stapling machines, particularly although not exclusively to the type used as office appliances.

It is within the contemplation of this invention to provide a stapling machine having a staple-strip carriage adapted to be pulled out forwardly from the body of the structure, thereby exposing the staple-carrying member and rendering same readily accessible for loading and unloading, the machine having a staple-driving member which is at all times in proper operative position with respect to the foremost staple to be driven. In this aspect of my invention it is an important object to obviate certain known shortcomings of other commercial devices having pull-out carriages, particularly the misalignment of the staple driver and the foremost staple upon the operative retraction of the carriage, generally resulting in binding, clogging and inoperativeness.

In the accomplishment of the above-mentioned objective it is a further object of this invention to employ a novel form of pull-out carriage member connected to the head or driving portion of the machine, whereby both carriage and driving head are simultaneously movable forwardly, and thereby at all times maintained in a mutually fixed relation. In this aspect of my invention it is a further object to provide novel means for maintaining a strip of staples in fixed relative position with respect to the staple-carrying member and the head for both projected and retracted positions of the carriage.

Another object of my invention is to provide a one-piece connection between the said carriage and driving head, thereby facilitating the construction of the device and enhancing its rigidity. It is also an important object, in connection with the carriage-head unit, to enable the components thereof to be readily assembled and disassembled without the use of special tools, and to provide the assembled components with means for maintaining them in spring-locked immovable relation, so that the said components will not be dislodged or jarred from their locked positions by impacts and vibrations of the device during its operative use.

It is also within my contemplation to provide a stapling machine having a pull-out carriage and head of the type above-mentioned, and which will be maintained positively locked both in projected and retracted positions. In this aspect of my invention it is an object to provide the forward and rear locking portions with retaining means for maintaining the internal components against displacement.

Still a further object of my invention is to provide a staple-strip carriage with staple-supporting means which will operatively maintain a strip of staples in proper position for longitudinal movement, and at the same time provide adequate finger clearance to enable the strip to be readily placed within the machine, or removed therefrom.

Another object of my invention is to provide means for the automatic retraction of the pulled-out carriage and head member. In this aspect of my invention it is an important object to employ the staple-strip feed spring for the purpose of applying a yieldable pull on the pulled-out carriage member, thereby facilitating its retraction.

Other objects, features and advantages will appear from the drawings and the description hereinafter given.

Referring to the drawings,

Figure 1 is a perspective view of the stapling machine embodying my invention, the pull-out carriage being

2

shown in its extended staple-loading position, the knob and fragments of the device being removed for clarity, a fragment of a staple strip being shown above the magazine prior to loading.

5 Figure 2 is a side elevation of Figure 1, the driver knob and base being shown in section, the magazine and driver member being shown in pivotally raised position with the pull-out carriage extended.

Figure 3 is a section of Figure 2 taken along line 3—3.

Figure 4 is a bottom view of the base of Figure 2.

Figure 5 is a perspective view of the carriage locking mechanism, a portion of the casing therefor being broken away for clarity.

15 Figure 6 is a longitudinal section, of the device of Figure 1, with the carriage member in its fully retracted and operative position, parts being shown in elevation for clarity.

Figure 7 is a section of Figure 6 taken along line 7—7.

Figure 8 is a section of Figure 6 taken along line 8—8.

Figure 9 is a section of Figure 6 taken along line 9—9.

20 Figure 10 is a fragmentary vertical section, partly in elevation, of the device of Figure 1.

Figure 11 is a somewhat enlarged fragmentary side elevation of the rear portion of the device of Figure 1.

25 Figure 12 is a section of Figure 11 taken along line 12—12.

Figure 13 is a disassembled perspective view of the components constituting the sub-assembly of the pull-out staple carriage and driver unit.

Figure 14 is a fragmentary longitudinal sectional view of the forward portion of the sub-assembly of Figure 13.

Figure 15 is a vertical section of Figure 14 taken along line 15—15.

30 Figure 16 is a fragmentary bottom view of Figure 14, and

Figure 17 is a perspective view of the tubular housing for the staple magazine portion of Figure 13, a fragment being broken away for clarity.

In the preferred form of my invention as illustrated, 40 the combination magazine and driver unit 20 is pivotally mounted at 21 on the upright walls 22, the latter being part of the U-shaped strap 23 the bottom connecting piece 24 underlying the base member 25 and being secured thereto by the fasteners 26. In underlying engagement with said connecting piece 24 and attached thereto by said fasteners 26 is the flat spring 27 carrying at the forward portion thereof the stop member 28 extending vertically through the aperture 29 of base 25. The upper terminal of said stop member 28 is adapted for engagement with the bottom wall 30 of pivotal unit 20 when it is in its lowermost position (see Figure 6), said wall constituting the base of the magazine housing 31, as will more clearly hereinafter appear. The arrangement is hence such that the yieldably supported member 28 serves as a shock-absorber in receiving the impact of pivotal member 20 during a downward movement thereof, the spring action of member 28 yieldably urging the entire unit 20 into a position where the forward portion 32 of bottom wall 30 is spaced above the staple-receiving anvil 33 of base 25. Said member 20 is further held against upward movement and in its horizontal operative position by the round-headed pin 34 extending through aperture 35 in the lateral wall 36 of the main body housing 37, said pin partially underlying the lip 38 of said wall 22 when the pin is in the projected position shown in Figures 11 and 12. The said pin 34 is mounted on the flat spring 39 anchored at 40 to the said wall 36, said pin acting as a yieldable detent when member 20 is pivotally raised, the spring 39 retracting to the dot-dash positions shown in Figure 12.

Disposed between the bottom portions 41 of the said lateral walls 36 of main body housing 37, and extending longitudinally therealong, is the said tubular magazine housing 31, whose lateral walls 42, base 30 and intermediate horizontal walls 43 form a lower compartment 44 communicating with the upper narrower compartment 45 formed by the upper lateral walls 46 and the top wall 47. The said base 30 contains the longitudinally apertured portion 48 the forward and rear terminals 49 and 50 thereof serving as limiting stops for the operative movement of the pull-out staple magazine and driver

unit, as will more clearly hereinafter appear. Attached to upper wall 47 of magazine housing 31, at anchorage 51 thereof, is the flat spring member 52 the forward portion of which carries the downwardly extending rear pusher stop 53 (see Figures 10 and 17), said stop extending through aperture 54 in wall 47. The forward portion of stop 53 has a sloping cam surface 55 adapted to be engaged by the rear upstanding wall 56 when the pusher 57 is being assembled in place, as will more clearly hereinafter appear, to give the stop 53 upwardly against the action of spring 52, whereby said wall 56 will be permitted to move rearwardly beyond the stop 53 to the position shown in Figure 10. The walls 42 and 43 of the tubular housing 31 also contain the forwardly disposed apertured portions 58, to receive therethrough certain carriage locking elements to be hereinafter described.

Slidably disposed within tubular housing 31 is the carriage member 59 comprising the horizontal staple magazine portion 60 and the vertical driver head portion 61. The magazine portion 60 comprises two parallel spaced staple rails 62 extending longitudinally along member 60 between forward and rear blocks 63 and 64, said rails being connected at their lower edges by the transverse wall 65 (Figures 7 to 9 and 13), the staple rail member being disposed within the channel 66 comprising the vertical walls 67 and the bottom connecting wall 68, the forward portion of bottom wall 68 containing the lateral slits 69 (Figure 16).

Extending between blocks 63 and 64 (Figure 6) and between the rails 62 is the guide rod 70. Slidably mounted over said rod is the pusher member 57 (Figure 16), comprising a substantially channel-shaped member with vertical walls 71 slidably disposed between rails 62 and lateral walls 67 of channel 66, the upper raised portion 72 of the pusher having attached thereto the longitudinally disposed strip 73 the rear portion of which comprises the aforementioned upstanding wall 56 and the forward portion of which consists of a downwardly extending wall 74 with an aperture 75 through which extends the rod 70. Also disposed over said rod 70 is the pusher spring 76 in abutting engagement with rear block 64 and the said wall 74 of the pusher member 57. The arrangement is hence such that the spring 76 would yieldably urge the pusher member 57 forwardly. The walls 71 of the pusher member are proportioned for abutment with the rear of a staple strip of predetermined dimensions, in conventional manner, whereby the pusher will yieldably urge such a staple strip mounted over rails 62 forwardly towards the driving head of the machine, as will more clearly hereinafter appear. The lateral walls 67 of channel 66 are recessed at 77, to expose the sides of a staple strip mounted on the rails, whereby finger room is provided for convenient handling of a strip of staples.

The forward portions of walls 67 of carriage member 59 contain the notches 78, and the rear portion of said walls contain the notches 79, said notches being adapted to receiving carriage-locking elements, as will more clearly hereinafter appear, for holding the pull-out carriage against movement from its forward and retracted positions.

The front of channel 66 (Figure 13) contains the two upright parallel walls 80, these being preferably integral with the lateral walls 67 and extending at right angles thereto. Said walls 80, which flank the front block 63, constitute the structural support for the driver head of the device, the components of said head portion being operatively mounted in place over said walls, in a manner to be hereinafter described.

The resilient retainer member 81 (Figure 13) is adapted for slidable assembly between walls 80, member 81 comprising two resilient walls 82 with upper outwardly extending flanges 83, the lower portion of the member comprising a raised central portion 84 containing thereon an upwardly extending spring retaining post 85. Portion 84 is formed by upper horizontal wall 86 and the two side walls 87, the latter being in spaced relation to walls 82. Said last-mentioned walls contain opposite apertures 88 which, when the member 81 is in assembled relation between walls 80, are in registry with the holes 89 in walls 80, there being correspondingly disposed holes 90 in walls 87. The pin 91 is inserted through said holes 88, 89 and 90, thereby maintaining member 81 fixed relative to walls 80. The opposite

terminals 92 of pin 91 are flush with the outer surfaces of walls 80. The parts are so proportioned that when member 81 is operatively in place, the lowermost walls 93 are spaced above the upper edges of rails 62, as clearly shown in Figure 15, to provide a clearance for accommodating either the foremost positioned staples 94, or the foremost portion of the staple-strip pusher 57.

Proportioned for slidable assembly over walls 80 is the outer driver casing 95, the said flanges 83 of retainer 81 overlapping the upper edges of casing 95 when in its assembled position (Figure 15). The resiliency of walls 82 enables such walls to flex inwardly during the downwardly sliding movement of casing 95, said walls snapping back into their vertical retaining position when casing 95 is brought down to its final lowermost position. The rear wall 96 of casing 95 has the apertured portion 97 at the bottom thereof shaped to conform to the outer contour of the pusher 57, to permit such pusher and the staples actuated thereby to enter the lower portion of casing 95. The front wall 98 of the casing serves not only as one of the lateral enclosing walls of the driver head, but also as a stop to receive thereagainst the foremost staple (Figure 14). The rear wall 96 (Figure 14) carries on the outside thereof a flat spring member 99, attached thereto at 100, said spring carrying the plunger stop pin 101 extending inwardly into the casing through the hole 102 thereof.

Disposed within casing 95, and vertically movable therein, is the plunger 103 (Figures 13 and 14) to the top of which is attached the knob base plate 104 from which downwardly extends the spring post 105. The rear wall 106 of plunger 103 contains the vertically slotted portion 107 through which extends the said stop pin 101. The front wall 108 of the plunger contains the hole 109 through which extends the plunger pin 110 of the plunger blade 111.

When the parts are assembled, as clearly indicated in Figures 6, 14 and 15, the said blade 111 is in slidable engagement with the front wall 98 of casing 95, the rear wall 106 being slidably engageable with the rear wall 96 of said casing 95, the side walls 112 and 113 being slidably engageable with the said walls 82 of retainer 81. The spring 114, mounted over posts 85 and 105, is in engagement with the under-side of knob plate 104 and wall 86 of the retainer member 81.

The arrangement is hence such that the plunger 103 together with the plunger blade 111 are urged upwardly under the action of spring 114, and are movable downwardly into an operative driving position, against the action of spring 114, when a downward pressure is applied to the knob 115 superimposed over plate 104. The slotted portion 107 is proportioned to limit the stroke of the driving mechanism, the pin 101 being engageable with slot terminals 116 and 117 to limit the movement of the plunger. The reciprocal actuation of the plunger 103 causes the plunger blade 111 to move therewith, the lower edge 118 of which is adapted to engage the crown of an underlying staple, to operatively eject it through the outlet space 119.

It should at this point be observed that the disassembly of the driving head can be as readily effected as the assembly of the components. The rearward retraction of spring 99 will disengage the pin 101 from the slotted portion 107 of plunger 103, whereby the plunger can readily be withdrawn from casing 95, together with blade 111. Thereafter a slight inward retraction, by manual pressure, of the resilient walls 82 will free the upper edges of casing 95 from the flanges 83, enabling said casing to be withdrawn. The pin 91 can be pushed out with any simple tool, whereupon member 81 is withdrawn.

The entire carriage member is slidably disposed within tubular casing 31, as aforesaid, and is movable between a retracted operative or driving position as shown in Figure 6, to a pulled-out loading position as shown in Figures 1, 2 and 10. The device is provided with a retractable locking mechanism adapted to hold the carriage firmly in either its retracted or loading positions, the said locking mechanism, generally identified by the reference numeral 120, being disposed at the forward portion of housing 37.

The said locking mechanism comprises a bracket 121 of inverted U-shaped cross-section, the lateral walls 122 and 123 thereof being secured by pins 124 to the lateral walls 36 of housing 37. Supported by and extending

downwardly from connecting wall 125 of bracket 120 is the guide rod 126 over which is slidably mounted the cross-bar 127 of the retractable lock unit 128 the downwardly extending legs 129 of which contain locking terminals 130. Mounted over rod 126 and disposed between walls 125 and 127 is the spring 131, yieldably urging member 128 downwardly. The said legs 129 contain therein oppositely disposed holes 132 through which extend the lock-actuating pin 133, said pin extending downwardly through the vertical slotted portions 134 of the lateral walls 36 of housing 37 (Figures 2, 5, 6, 9 and 10). Mounted upon pin 133 at opposite terminals thereof are the buttons 135 adapted to be actuated manually upwardly against the action of spring 131. It will be observed that the said legs 129 of locking unit 128 are slidably disposed within slotted portions 136 in the opposite walls 122 and 133 of bracket 120, thereby permitting a vertical reciprocating motion of said locking member 128.

The said spring 131 yieldably urges member 128, as aforesaid, downwardly, the lower terminals 130 thereof being urged into engagement with the upper edges of the walls 67 of channel 66, the said terminals 130 extending through the apertured portions 58 of tubular casing 31. However, when the carriage member 59 is pulled out to its fullest extent, the rear recessed portions 79 of walls 67 will be in registry with apertured portions 58, so that the said terminals 130 will yieldably enter the said recessed portions 79 to hold the pulled-out carriage member locked in its loading position. To retract the carriage member into its operative position, the two buttons 135 are again upwardly manipulated against the action of spring 131, thereby retracting the member 128 upwardly and removing the said terminals 130 from their obstructing positions. The entire carriage member 59 is now free to be moved inwardly. It should be noted, however, that when the carriage member was in its pulled-out position, the pusher spring 76 was in its maximum extended and strained condition, so that it would be exerting an inward pull on the carriage member. Accordingly, when the locking unit 128 is operatively raised, as aforesaid, the said pusher spring 76 will exert an inward retracting pull upon the carriage 59, thereby facilitating the return of the carriage into its operative position.

It will be observed that the rear portion of the carriage member contains the setscrew 137 (Figures 2 and 10) which extends through the slot 48 in the base wall 30 of tubular casing 31. This setscrew is engageable with the front and rear extremities, 49 and 50, respectively, of slot 48, whereby it serves as a supplementary stop to limit the operative movements of the carriage. In other words, when the buttons 135 are operatively in raised position and the carriage member free for movement, the said screw stop 137 will prevent the carriage from being inadvertently pulled out of the machine, and will also limit the innermost movement thereof.

To load the device, the carriage 59 is pulled outwardly, as aforesaid, whereby the staple rail 62 will be exposed. The strip of staples 138 (Figure 1) is then positioned upon said rails, inside of walls 67. Since there are recessed portions 77 of walls 67, as aforesaid, access is readily provided to the rails for proper positioning of the staples. Said recesses 77 also provide sufficient finger room to enable the staples to be operatively manipulated forwardly or rearwardly, or lifted out of the magazine. After the loading, the carriage is operatively retracted, in the manner aforesaid, to its driving position. The staple-driving portion is effectuated as above indicated, merely by depressing the knob 115.

It is of primary importance to observe that the pulling out and retraction of the carriage member 59 cannot, in my invention, affect or in any way alter the relationship between the plunger blade 111 and the foremost staple to be driven. This is due to the fact that the driving head and staple magazine portions are both contained in a single sub-assembly unit, with the driving casing at all times maintained in immovable relation with respect to the staple magazine. To assure such an immovable relationship, it is preferred that the upright walls 80 be made, as shown in the drawings, integral with the walls 67 of channel member 66. In the arrangement shown, the walls 67 and 80 are both formed from a single flat sheet of material, thereby not only providing the rigid structure desired, but also facilitating

the fabrication of this device. Since the walls 80 are the structural members upon which the entire driving head is supported, the fixed relation of walls 80 with respect to walls 67 will provide for the entire driving-head portion a corresponding fixed relation to the entire staple magazine. This applies regardless of the position in which the carriage member may be disposed. The arrangement completely eliminates the disadvantage inherent in other pull-out structures in which, upon a return of the pulled-out carriage, the former registry of the driver with the foremost staple is disturbed or altered. Because of this feature in my invention, there is always ease of action of the plunger without binding, and without the danger of the clogging of staples.

It will also be noted that all the assembled components in the driving portion of the machine are spring-locked, and that the slideable carriage member is similarly spring-locked in both its loading and driving positions.

The arrangement is hence such that the assembled parts of the unit are firmly maintained against displacement during the operative use of the machine.

In the above description, the invention has been disclosed merely by way of example and in preferred manner; but obviously many variations and modifications may be made therein. It is to be understood, therefore, that the invention is not limited to any specific form or manner of practicing same, except insofar as such limitations are specified in the appended claims.

I claim:

- 30 1. In a stapling machine, a main body member, a tubular casing rigidly mounted in said main body member, a pull-out carriage member slidably disposed within the tubular casing and movable between a retracted operative position and an extended loading position, said tubular casing supporting said carriage member in each of said positions, the carriage member comprising a staple magazine and a driver head portion at the front of the magazine and communicating therewith, plunger means in the said head portion operatively movable along a path extending perpendicularly to the plane of the staple magazine, a driver casing for said plunger means, and a driver-head support extending upwardly from and being in fixed relation to the front of said magazine.
- 35 2. In a stapling machine, the combination according to claim 1, said driver-head support comprising two parallel upright walls; said driver casing being mounted over the outer surfaces of said walls, said plunger means being slidably disposed within said driver casing.
- 40 3. In a stapling machine, the combination according to claim 1, said driver-head support comprising two parallel upright walls; said driver casing being mounted over the outer surfaces of said walls, said plunger means being slidably disposed within said driver casing, and a retainer member having two resilient walls in engagement with the inner surfaces of said upright walls, the upper portions of said resilient walls having outwardly extending flanges in overlying retractable engagement with the upper edges of said driver casing, whereby the driver casing is maintained against displacement.
- 45 4. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly extending flanges in overlying retractable engagement with the upper edges of said driver casing, whereby the driver casing is maintained against displacement, the lower portion of said retainer member having a transverse wall, and a spring in engagement with said transverse wall and the said plunger means, said spring urging said plunger means upwardly into its inoperative position.
- 50 5. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly
- 55 6. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly extending flanges in overlying retractable engagement with the upper edges of said driver casing, whereby the driver casing is maintained against displacement, the lower portion of said retainer member having a transverse wall, and a spring in engagement with said transverse wall and the said plunger means, said spring urging said plunger means upwardly into its inoperative position.
- 60 7. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly extending flanges in overlying retractable engagement with the upper edges of said driver casing, whereby the driver casing is maintained against displacement, the lower portion of said retainer member having a transverse wall, and a spring in engagement with said transverse wall and the said plunger means, said spring urging said plunger means upwardly into its inoperative position.
- 65 8. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly extending flanges in overlying retractable engagement with the upper edges of said driver casing, whereby the driver casing is maintained against displacement, the lower portion of said retainer member having a transverse wall, and a spring in engagement with said transverse wall and the said plunger means, said spring urging said plunger means upwardly into its inoperative position.
- 70 9. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly extending flanges in overlying retractable engagement with the upper edges of said driver casing, whereby the driver casing is maintained against displacement, the lower portion of said retainer member having a transverse wall, and a spring in engagement with said transverse wall and the said plunger means, said spring urging said plunger means upwardly into its inoperative position.
- 75 10. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly
- 80 11. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly
- 85 12. In a stapling machine, the combination according to claim 1, said driver-head support comprising two parallel upright walls; said driver casing being mounted over the outer surfaces of said walls, said plunger means being slidably disposed within said driver casing, a retainer member having two resilient walls in engagement with the inner surfaces of said upright walls, the upper portions of said resilient walls having outwardly

extending flanges in overlying retractable engagement with the upper edges of said driver casing, whereby the driver casing is maintained against displacement, the lower portion of said retainer member having a transverse wall, a spring post extending upwardly from said transverse wall, said plunger means having a knob member with a spring post extending downwardly therefrom, and a spring mounted over both of said posts and in engagement with said transverse wall and said knob member, for urging said plunger means upwardly into its inoperative position.

6. In a stapling machine, a main body member, a tubular casing rigidly mounted in said main member, a pull-out carriage member slidably disposed within the tubular casing and movable between a retracted operative position and an extended loading position, said tubular casing supporting said carriage member in each of said positions, the carriage member comprising a staple magazine and a driver head portion at the front of the magazine and communicating therewith, plunger means in the said head portion operatively movable along a path extending perpendicularly to the plane of the staple magazine, a driver casing for said plunger means, a driver-head support extending upwardly from and being in fixed relation to the front of said magazine, said driver casing being mounted upon said support, said driver casing having a rear wall and a retractable driver stop pin on said rear wall, said plunger means having a vertically slotted wall through which said stop pin extends, for limiting the stroke of the plunger means.

7. In a stapling machine, a main body member, a tubular casing rigidly mounted in said main body member, a pull-out carriage member slidably disposed within the tubular casing and movable between a retracted operative position and an extended loading position, said tubular casing supporting said carriage member in each of said positions, the carriage member comprising a staple magazine and a driver head portion at the front of the magazine and communicating therewith, plunger means in the said head portion operatively movable along a path extending perpendicularly to the plane of said staple magazine, a driver casing for said plunger means, a driver-head support extending upwardly from and being in fixed relation to the front of said magazine, said driver casing being mounted upon said support, said driver casing having a front wall, said plunger means having a front wall, a plunger blade, and interengaging means on said front wall and said plunger blade for removably holding said plunger blade in fixed relationship to said front wall, said blade being in slidable engagement with said front wall of the driver casing.

8. In a stapling machine, a main body member, a tubular casing rigidly mounted in said main body member, a pull-out carriage member slidably disposed within the tubular casing and movable between a retracted operative position and an extended loading position, said tubular casing supporting said carriage member in each of said positions, the carriage member comprising a staple magazine and a driver head portion at the front of the magazine and communicating therewith, plunger means in the said head portion operatively movable along a path intersecting that of the pusher means, a driver casing for said plunger means, a driver-head support extending upwardly from and being in fixed relation to the

10 front of said magazine, said driver casing being mounted upon said support, said driver-head support comprising two parallel upright walls, said driver casing being mounted over the outer surfaces of said walls, said plunger means being slidably disposed within said driver casing, and a retainer member having two resilient walls in engagement with the inner surfaces of said upright walls, said plunger means having two side walls in slidable engagement with the inner surfaces of said two resilient walls.

9. In a stapling machine, a base member, a main body member pivoted to said base member, a tubular casing rigidly mounted in said main body member, a pull-out carriage member slidably supported within the tubular casing and movable between a retracted operative position and an extended loading position, the carriage member comprising a staple magazine and a driver head portion at the front of the magazine and communicating therewith, plunger means in the said head portion operatively movable along a path extending perpendicularly to the plane of the staple magazine, spring means attached to said carriage member and in strained condition when said member is in its said extended loading position, whereby the carriage member is yieldably urged inwardly from its loading position toward its said retracted position, a locking member in interlocking engagement with said carriage member when in its said loading position, whereby the member is held in said loading position against the action of said spring means, and releasing means for said locking member.

10. In a stapling machine, a main body member, a tubular casing rigidly secured in said main body member, a pull-out carriage slidably mounted in said tubular casing, cooperating means on said casing and said carriage 35 to prevent complete separation thereof, said casing having walls fitting snugly against said carriage to support said carriage in any position to which it may be moved, said carriage being movable between a retracted operative position and an extended loading position, the carriage member comprising a staple magazine and a driver head portion secured to the front of the magazine in rigid relationship thereto, the base of the tubular casing having a longitudinally slotted portion having a length equal to the distance the carriage moves between its retracted and extended positions, a stop pin secured to the rear of the carriage and extending into said slotted portion for engagement with the opposite terminals thereof to limit the longitudinal movement of the carriage.
